UNITED STATES PATENT OFFICE.

ROSS CLIFF STEWART, OF MOUNT ROYAL, AND WILLIAM ALEXANDER DUFF, OF MONTREAL, QUEBEC, CANADA.

DOOR STRUCTURE.

Application filed April 9, 1927. Serial No. 182,367.

- The invention relates to a door structure, as described in the present specification and illustrated in the accompanying drawings that form part of the same.
- 5 The invention consists essentially of the novel features of construction pointed out broadly and specifically in the claims for novelty following a description containing an explanation in detail of an acceptable 10 form of the invention.

The objects of the invention are to overcome the difficulties incident to the warping of doors or other dislocation thereof, occurring frequently in swinging doors of a heavy 15 type, in which the weight is often a deterrent factor in effecting a good closure; to increase the stability of the structure and at the same time insure economy in regard to the combined cost of installation and maintenance; 20 to eliminate the disastrous results from leakages in inclement weather in engine houses and warehouses requiring free openings and tight closures to such openings; to produce these doors at a reasonably low cost according 25 to specifications and to dimensions and to standardize the construction in so far as the kind and description of the material and shapes of the parts are concerned; and generally to provide an efficient, economical and 30 durable door.

In the drawings, Figure 1 is a front elevation of the doors and doorway frame.

Figure 2 is an elevation showing the framework of the two doors.

35 Figure 3 is a cross sectional view through one door and a post on the line 3—3 in Figure 2.

Figure 4 is a cross sectional view through one door and a post on the line 4—4 in Figure 2.

40 Figure 5 is an enlarged sectional detail showing nailing strips.

Figure 6 is a vertical sectional view on the line 6—6 on Figure 2 showing the door and 45 posts.

Figure 7 is an enlarged sectional detail of the wicket door and framework.

Figure 8 is an enlarged detail showing a plan view of the assembled hinge parts.

50 Figure 9 is an enlarged detail showing the latching mechanism for holding the doors open.

Figure 10 is a detail showing an outline of the doors and adjustable bottom plates.

55 Figure 11 is a detail showing an outline of

the doors in a sagged position with the bottom plates adjusted.

Like numerals of reference indicate corresponding parts in the various figures.

Referring to the drawings, the doors 15 60 and 16 form the closures in the doorway formed by the posts 17 and 18 and transverse girder 19. Each door is formed of a rectangular frame in which the vertical I-beams 20 and 21 are welded to the horizontal I- 65 beams 22 and 23, and to the diagonal I-beam 24, which extends from an inner and upper corner angle to an intermediate corner angle formed at the junction of the intermediate transverse I-beam 25 and the outer vertical 70 I-beam 20, thereby forming an open frame, in which the boundary I-beams 20, 21, 22 and 23 are of greater dimensions than the diagonal and intermediate transverse interior I-beams, the latter being laid on their 75 sides instead of standing out on their ends.

The inner channels or recesses of the boundary I-beams are filled with wood 26, shaped to fit into the channels and extending therebeyond in a flush surface 27 with the 80 outer faces of the I-flanges.

The spacers 28 formed by the blocks or strips are mounted on the wood fillings 26, and secured to boundary channels by the 85 bolts 29 and nuts 30.

The sheathing 32 is only indirectly attached to the frame and has flush surfaces throughout on either side of the door, being nailed to the nailing strips 31 and 31^a and the spacing strip 28. The sheathing is of wood 90 and therefore warping does not affect the metal frame. So far as ordinary breakages are concerned, in this comparatively light sheathing, repairs may be readily accomplished independently of the frame as it is 95 not uncommon for a door to receive a knock, especially in engine houses, which puts a hole completely through the door. In such happenings usually both frame and wood break and this necessitates a new door, 100 whereas in this invention, the wood is fractured only and is readily replaced.

This sheathing or boarding 32 is arranged in exactly the same way on either side of the door, and is flush with the flush surfaces 27, 105 being nailed to the nailing strips 31 and 31^a in the spacing strips 28, thereby forming with the boundary I-beams the outside and inside surfaces of the door, in which it will be seen that these covering surfaces, namely 110

the sheathing, are of wood, independent in so far as warping is concerned, of the metal frame, in fact, really free from said frame in so far as ordinary breakages are concerned, 5 for the comparatively light sheathing may in parts be thoroughly dislocated, without affecting the frame at all, as it is not uncommon for the door to receive a knock, especially in engine houses, which puts a hole 10 completely through the door, and in the case where frames and wood are worked up together, naturally the frame goes with the wood, but here where they are to all intents and purposes separate, the sheathing will be 15 broken as it is the point of least resistance and can be repaired readily without disturbing the frame-work.

The hinges carrying these doors, and there are preferably three each is formed of the lugs 20 38 projecting from the lug bases 34, these lug bases, being welded to the web of the I-beam 21, one hinge lug being towards the upper end of the I-beam 21, another in the 25 centre thereof and another towards the lower end.

These lugs are pierced for the hinge pins 35. Each of the hinge pins 35 is formed like a bolt having the squared head 36 and the threaded end 37, on which is mounted the 30 adjusting nut 38, held by the lock nut 39 to its adjusted position.

The hinge pins 35 are mounted in the plates 40, each plate 40 having parallel flanges 41 and 42, the flange 42 being slotted at 43 to 35 form a square hole for the square head 36 of the hinge pin, the flange 41 having a pin hole 44 through which the pin extends.

The washer 45 is mounted on the pin 35 between the lug 33 and the flange 42 and the 40 washers 46 and 47 are mounted on the pin 35 between the nut 38 and the flange 41, thus by loosening the lock nut 39 the pin can be drawn upwardly by screwing on the nut 38, or downwardly as the case may be, and 45 this lifts the door or lowers it at that point. Naturally the three hinges have to be adjusted so as to bring them in cooperating positions to hang the door correctly.

Each door 15 and 16 has its own complement of three hinges, and adjoining doors in engine house work can have a double plate, such as illustrated, with a hinge pin at each 50 end for adjoining doors. Such construction is naturally only a matter of convenience and 55 may be changed at will to suit the particular installations, in fact various differences of construction are bound to occur for the several uses to which the door may be put.

At the lower end of each door, a skirting plate 48 is mounted, this plate having the 60 slots 49, through which the bolts 50 are inserted into and through the door to hold said plate in its adjusted position.

This construction is very necessary, espe-

cially in engine house door structures, where 65 there is liable to be a sagging of a post due to excessive use of certain stalls and where there is such a sagging, the whole frame of the door will lean over slightly, and this makes it necessary to adjust these skirting plates to bring 70 the bottom thereof on a level with the concrete of the flooring, and that inclines them slightly on the door to which they are held by the said bolts. Naturally the bolts are loosened to 75 adjust the posts of these skirting plates and are then tightened up again.

The doors in engine houses swing outwardly and meet or nearly meet at their outer edges. Therefore there is a bumper post secured in the concrete flooring, and this 80 bumper post 51 carries two plate latches 52 and 53 pivotally secured on the bolt 54, on said post and are formed to fall into the outer channels of the vertical beams 20 thereby locking the doors very securely to their open 85 position, which is very essential in engine houses, when the locomotives are leaving their stalls. Naturally to close the doors the latches are lifted and the doors simply swung to their closed positions, where they are held 90 by the locking bar 55 which is pivoted at 56 on one of the doors and slides behind the part round chafing bars 57, these bars being secured to the transverse intermediate bars 95 25 of the frame-work of the doors.

In the door 16 a short vertical I-beam 58 is introduced between the intermediate I-beam 25 of that door and the horizontal I-beam 23 of that door and welded to these transverse beams.

In the wicket door opening a wood filling 59 is introduced into the several channels on two sides, and over this filler the wood strips 60 are mounted having the door jamb 61 formed by reducing the outer side of the 105 strip.

These strips 60 are held to the filler and to the channels of the I-beams 20, 23 and 25 by the bolts 62 and nuts 63.

The fourth side of the bounding opening is 110 completed by the wooden strip 64 slotted from the outer side to form a door jamb 65, said strip 64 being held to an end face in the short beam 58 by the bolts 66 and nuts 67, said bolts 66 extending through the I-flanges of the 115 beam 58, through the filler strips 68 and 69 in the channels of the said I-beam 58 and through the wooden spacer 70 abutting the other end of the I-beam 58, the sheathing of the door being flush with the strip 64 and 120 nailed to the door frame 71.

In the operation, these doors swing on their hinges, and in order that they may be perfectly true in the hanging, the nuts on the hinge pins are all adjusted to the greatest nicety, so that no door lug or no plate flange is bearing more than its just share of the weight of the door and in this position each 125

door will swing truly and perfectly, and its weight be evenly distributed in the doorway frame.

It has already been explained how the plates are adjusted at the lower ends of the doors, said adjusting only being necessary when the door frame changes by settling, such changes are very slight and almost imperceptible, but even so it is necessary to adjust just the skirting plates to prevent the doors hitting the sill. In every other respect the doors operate just the same as the conventional type of engine house doors. The frames of the doors carry the light sheathing which is so easily repaired or replaced and which contributes to the reduction of the weight of doors used for such purposes.

What we claim is:

1. A door structure, comprising a metal frame formed of I-beams in vertical, horizontal and diagonal arrangement, nailing strips secured in the recesses of said beams

and wooden sheathing on the inside and on the outside and secured to said nailing strips and forming inner and outer coverings supported by said I-beams. 25

2. A door structure comprising metal I-beams and hinge pieces welded together to form a swinging interior and boundary frame supporting wooden blocks and strips bolted thereto, and tongued and grooved wooden boards secured to said blocks and strips and enclosing said frame on the inside and on the outside and forming therewith the closure. 30

3. A door structure comprising an I-beam frame in rectangular sections and having a diagonal I-beam brace in the upper section, nailing strips rigidly secured to the several I-beams, and sheathing nailed to said strips and closing in the beam brace. 35

Signed at Montreal, Canada, this 31st day of March, 1927.
